Primary Examiner — Katherine Glennon*Assistant Examiner* — Yuan Yuan(74) *Attorney, Agent, or Firm* — Volpe Koenig P.C.; Daniel E. Rose(57) **CLAIM**

The ornamental design for a game controller with touchscreen, as shown and described.

DESCRIPTION

FIG. 1 shows a rear perspective view of a game controller with touchscreen.

FIG. 2 shows a front perspective view thereof.

FIG. 3 shows a top view thereof.

FIG. 4 shows a bottom view thereof.

FIG. 5 shows a left side view thereof.

FIG. 6 shows a right side view thereof.

FIG. 7 shows a rear view thereof; and,

FIG. 8 shows a front view thereof.

The broken lines in the Figures depict portions of the game controller with touchscreen that form no part of the claimed design.
